tion of Delaware

Application January 28, 1933, Serial No. 653,946

8 Claims. (Cl. 250—20)

This invention relates to a method of and means for demodulating signal modulated waves. More in particular, this invention relates to a method of and circuit for receiving, amplifying and de-modulating waves, the phase of which varies in accordance with the signal.

The ordinary radio receiver is insensitive to phase modulation. Heretofore elaborate and complicated methods and means have been employed to receive and demodulate phase modulated waves.

The primary object of the present invention is to provide a new and improved method of and means for demodulating phase modulated waves, which method and means is simple in nature and efficient in operation.

In the method which I prefer, I use an oscillating detector of the autodyne type. The signal is passed through a radio frequency amplifier, the purpose of which is to raise the energy level of the signal to a suitable value and to maintain it there by a limiting action. This limiting action may be obtained in any manner. Preferably, it is obtained by passing the modulated wave through radio frequency amplifiers operating at saturation. The limited signal is then impressed on the autodyne detector circuit through a coupling coil and the degree of coupling carefully adjusted to give a signal level which is just sufficient to hold the oscillating detector in step with the incoming carrier when the detector has been adjusted to zero beat note. Inasmuch as the carrier is the most predominating frequency with ordinary modulation levels, attainment of this adjustment is not at all difficult.

The action of the detector under these circumstances is to supply a strong local carrier essentially locked in phase with the incoming carrier. In a sense, the oscillating circuit tuned to zero beat provides a very sharp filter and amplifier for the carrier frequency alone. When the incoming signal varies in phase with modulation, the effect is to vary the efficiency of the tuned circuit as far as the detector tube is concerned, i. e., when the incoming signal leads in phase, it will supply energy to the circuit and when it lags in phase it will effectively load the circuit.

This action may be best understood by analogy. Consider the tuned circuit to be an alternator with the detector tube as the driving motor. The incoming signal is an outside source connected to the alternator. When the signal voltage has the same phase as the alternator, there will be

no transfer of energy and the motor will be supplying the losses in the alternator. If the signal voltage advances in phase, it will tend to drive the alternator as a motor and relieve the load on the motor, and vice versa. Just as the driving motor current will react to these phase shifts, so will the detector plate current.

This circuit is sensitive and efficient for phase modulation reception. The receiver involves little more equipment than a simple receiver, such as 10 used for telegraph reception. As it involves no fixed filters, it may be used on any frequency directly and can be built much more cheaply and compactly than other types of phase modulation receivers.

The novel features of my invention have been pointed out with particularity in the claims appended hereto. My method of demodulating waves and a practical circuit for carrying out the same will be best understood from the following description thereof and therefrom when read in connection with the attached drawing, in which:

Figures 1 and 2 illustrate my phase demodulation circuit including the autodyne demodulating means.

In practice, my receiver would have the following components:

1. Means for intercepting the waves. This means may be an aerial system 1 of any appropriate type.

2. Means for amplifying the radio frequency signal to a suitable level. Amplifying in any manner the intercepted wave.

3. Means for limiting or controlling the maximum output of the amplifier. Any amplitude limiting device may be used. I propose to use a saturated radio frequency amplifier.

4. Means for coupling the output of the amplifier to the detector and means for controlling the value of that coupling.

5. An autodyne type of detector with means for controlling the tuning and strength of oscillations.

6. Suitable audio amplifiers and output circuits.

The aerial 1 is coupled by inductance 8 to the inductance 10 in the input circuit of the radio frequency amplifier 12. This input circuit is tuned to the frequency of the wave to be received by a capacity 11. An electrostatic shield of the type disclosed in United States Patent No. 1,942,575, issued January 9, 1934, or of any other type may be interposed between the windings 8 and 10. The control grid of tube 12 may be 55

biased to the desired operating potential by current from a source 13. The tube 12 may be of any type and is shown as a tube of the screen grid type. The anode of tube 12 is connected to a tuned circuit 14 including inductance and capacity in parallel.

While I have shown a single amplifier in the radio frequency amplifying stage, it will be understood that several amplifiers may be used if necessary to raise the signal to the desired level. The high frequency oscillations selectively amplified in the tube 12 are impressed from the oscillation circuit 14 by way of a coupling capacity 16 on to the control grid of a thermionic tube 18 in the limiting amplifier stage. The tube 18 has its control grid biased by way of resistance 17 and source 20 to operate at saturation so that the oscillations appearing in the output inductance 21, connected with the anode of tube 18, will be of constant amplitude. Here I have shown but a single tube in the limiting amplifier. If necessary several tubes may be used. Furthermore, the tubes may be of any type, although I have shown the tube 18 as being of the screen grid type. The screen grid electrodes of tubes 18 and 12 may be supplied with the desired potential by a lead 21 connected with the potential source 22.

The autodyne detector includes a thermionic tube 24 having its input electrodes connected with an input circuit comprising an inductance 25 and a capacity 31 in parallel and its output electrodes connected to a work circuit including the primary winding 26 of a transformer T. The anode circuit of 24 is inductively coupled to the input circuit by way of an inductance 27 and capacitively coupled to the input circuit by the capacity 28 in series with the inductance 27. Best results are obtained from this receiver if a sensitive control of regeneration in the autodyne detector is provided. For this reason regeneration is obtained by variable inductive and capacitive coupling between the output electrodes of the tube 24 and the input electrodes of the tube 24. When the signal is varying in intensity the limiter, including the amplifier 18, is an essential feature. As is well understood by those skilled in the art, the limiter serves to level off the amplitude of the signals as passed through the amplifier 18. This is to insure that the signal energy impressed on the input circuit 25 of the autodyne detector is just sufficient to hold this detector in step with the incoming signal. If more signal is impressed on the detector circuit than is necessary to just hold the detector in step, the detector will be pulled in phase with the incoming signal and the signal modulation will disappear from the output circuit of the detector. To further insure that the proper amount of signal energy is impressed from the final limiter tube 18 on to the autodyne detector 24, the inductance 21 in the output circuit of the tube 18 is variably coupled to the inductance in the input circuit 25 of the autodyne detector. An electrostatic shield, similar to the one between windings 8 and 10, may be interposed between 21 and 25.

Radio frequency oscillations are blocked out of the transformer T by a radio frequency choking inductance 34. As the incoming signal varies in phase with modulation the efficiency of the tuned circuit 25 is varied. When the incoming signal leads in phase the efficiency of the tuned circuit, as far as the detector circuit is concerned, will

decrease and the incoming signal will supply energy to the circuit. When the phase of the incoming signal lags the phase of the oscillations in the tuned circuit it will act in effect as a load on said circuit. This will cause the amplitude of the rectified currents in the output circuit of the autodyne 24 to vary in accordance with the signal modulation. These variations will be impressed by the transformer T on to the audio frequency amplifier tube 30, from which it may be impressed by a transformer T₁ on to any indicator. The tuning capacity 31 in the tuned circuit 25 may be shifted by a trimmer condenser 32 in order that a single control may be used for this tuning capacity and the tuning capacity in the prior stages.

Anode potentials for the tubes 12, 18, 24 and 30 may be supplied from separate sources or from the single source 22, as shown.

Although I have shown an autodyne detector operated in a novel manner to demodulate phase modulated waves, it will be understood that this method may be applied to a superheterodyne of the ordinary type, that is, the superheterodyne which includes a source of local oscillations. When this is done the limiting action and detecting in part of the amplification may be accomplished in the intermediate frequency amplifier. The second detector of the heterodyne, however, will be replaced by my novel autodyne detector including the adjustable coupling circuits and regeneration controls.

The method of and circuit for demodulating phase modulated waves as disclosed above has been used in practice by me and has proved to be efficient and successful in operation.

Having thus described my invention and the operation thereof, what I claim is:

1. A signal demodulating circuit comprising, an energy absorption member, a radio frequency amplifier having its input electrodes coupled to said absorption member, a second radio frequency amplifier having its input circuits coupled to the output circuits of said first named radio frequency amplifier, means for biasing the electrodes of said second named radio frequency amplifier to a potential at which it operates at saturation, an autodyne detector including a thermionic tube having variably coupled input and output electrodes, and a variable coupling circuit for loosely coupling said autodyne detector to the output electrodes of said last named radio frequency amplifier.

2. A signal demodulating circuit comprising, an energy absorption member, a radio frequency amplifier having its input electrodes coupled to said absorption member, a second radio frequency amplifier having its input electrodes capacitively coupled to the output electrodes of said first named radio frequency amplifier, a circuit including a direct current source for biasing the electrodes of said second named radio frequency amplifier to a potential at which it operates at saturation, an autodyne detector including a thermionic tube having inductive and capacitive coupled input and output electrodes, and an inductive circuit for loosely coupling said autodyne to the output electrodes of said last named radio frequency amplifier.

3. Means for demodulating signal carrying oscillations of substantially constant amplitude and of varying phase comprising, a signal responsive circuit, a radio frequency amplifier comprising a thermionic tube having an input circuit coupled to said signal responsive circuit and an output

circuit, means in one of said circuits to insure substantially constant amplitude of the signal modulated oscillations in said output circuit irrespective of amplitude variations in the signal modulated oscillations in said input circuit, demodulating means of the thermionic type having input and output circuits coupled to produce oscillations, and means for loosely coupling the input circuit of said demodulating means of the thermionic type to the output circuit of said radio frequency amplifier.

4. Means for demodulating signal modulated oscillations of constant amplitude comprising, a radio frequency amplifier operating at saturation, said amplifier having an input circuit to which said oscillations to be demodulated are applied and an output circuit, a second thermionic tube having input and output electrodes, an input circuit coupled between said input electrodes, said circuit including an inductance loosely coupled to an inductance in the output circuit of said first named tube, an output circuit connected between the output electrodes of said second named tube, and means including an inductance and a variable capacity for coupling said output circuit of said second named tube to the input circuit of said second named tube to insure the production of oscillations in said second named tube and circuits of constant amplitude.

30 5. A phase modulated wave demodulating device comprising, a thermionic tube having an anode, a cathode and a control grid electrode, a tuned inductance connected in series with an impedance between the control grid and cathode of said tube, an output circuit connected between the anode and cathode of said tube, said output circuit being coupled to indicating means, an inductance and a variable capacity connected between the anode of said tube and the cathode of said tube, said inductance being coupled to said first mentioned inductance, and variable loose coupling means for applying signal modulated oscillations of substantially constant amplitude to said first mentioned inductance.

45 6. Means for demodulating oscillations of constant amplitude but of a phase which varies at signal frequency comprising, a thermionic amplifier having input electrodes connected in an input circuit including biasing means and an inductance adapted to be energized by said oscillations

to be demodulated and output electrodes, the biasing means in said input circuit insuring operation of said amplifier at saturation whereby the amplitude of the oscillations on said output electrodes is constant irrespective of change in amplitude of the oscillations impressed on said inductance in said input circuit, the phase of said oscillations varying at signal frequency, a second thermionic tube having its input and output electrodes connected in circuits variably coupled to produce oscillations and tuned to a frequency which is the mean of the frequency of the oscillations to be demodulated, and inductive means coupled with the output electrodes of said first named tube and loosely coupled to the input circuit of said second named tube for applying the oscillations of constant amplitude and varying phase from the output electrodes of said first named tube to the input electrodes of said second named tube.

7. In a system having a stage of autodyne detection followed by at least one stage of amplification and useful for demodulation of phase-modulated signals, the method of detection of said signals which comprises loosely coupling said stage of autodyne detection with said stage of amplification, operating the amplification stage under a condition of such saturation as to substantially level off the amplitude of the received signals so that the signal level is just sufficient to hold the locally generated oscillations in step with the incoming carrier, and adjusting the frequency of the locally generated oscillations so as to maintain a zero beat note with said carrier.

8. In a system for demodulation of phase-modulated signals, the method of detection of said signals which comprises collecting, amplifying and leveling off the amplitude of an incoming phase-modulated radio-frequency wave, locally generating a strong carrier wave, loosely coupling the incoming wave to said locally generated wave, causing the locally generated wave to be adjusted in frequency and in phase so as to have a zero beat with the carrier component of said incoming wave, causing said locally generated wave and said incoming carrier wave component to be locked in step, and causing the strength of the locally generated wave to be varied in accordance with variations in the percentage of phase-modulation.
